BUMPER

Paul B. Nunn, P.O. Box 19043,
Oklahoma City, Okla. 73119

Filed June 29, 1970, Ser. No. 23,706

Term of patent 14 years

Int. Cl. D12—16

U.S. Cl. D14—6

FIG. 1 is a plan view of a bumper constructed in accordance with this invention.

FIG. 2 is a front elevation view of the bumper shown in FIG. 1.

FIG. 3 is a rear elevation view of the bumper shown in FIG. 1.

FIG. 4 is an end view of the bumper shown in FIG. 1.

FIG. 5 is a sectional view taken along lines 5—5 of the bumper illustrated in FIG. 1.

FIG. 6 is a sectional view taken along lines 6—6 of the bumper illustrated in FIG. 1.

The elements shown in broken lines are included for illustrative purposes only.

I claim:

The ornamental design for a bumper, substantially as shown and described.
